UNITED STATES PATENT OFFICE.

FRANK C. FAXON, OF SAN FRANCISCO, CALIFORNIA, ASSIGNOR TO THE
PACIFIC ACETYLENE GAS COMPANY, OF SAN FRANCISCO, CALIFORNIA,
A CORPORATION OF CALIFORNIA.

APPARATUS FOR GENERATING ACETYLENE GAS.

SPECIFICATION forming part of Letters Patent No. 684,501, dated October 15, 1901.

Application filed January 21, 1899. Serial No. 702,953. (No model.)

To all whom it may concern:

Be it known that I, FRANK CLAYBURN FAXON, a citizen of the United States of America, and a resident of the city and county 5 of San Francisco, in the State of California, have invented a new and useful Apparatus for Generating, Cooling, and Drying Acetylene Gas, of which the following is a specification.

10 The object of my invention is to provide a practical machine that will work automatically and generate cool dry acetylene gas in large quantities and which may be used with or without a gasometer. I have endeavored 15 to combine simplicity and utility. I have found the art covered by a great many patents; but many of the devices were only sufficient for generating a small quantity of acetylene gas at a time. Of all the machines 20 intended to generate large quantities of gas none that I have seen are entirely practical.

I claim for my invention that it is simple, automatically regulates the quantity of gas generated and the rapidity of generation to 25 correspond to the consumption, and that it produces a cool, dry, and pure gas ready for immediate use.

In the accompanying drawings, which form a part of this specification, Figure 1 is a side 30 elevation of the entire machine, showing the generator in section and part of the side and end of the cooler broken away. Fig. 2 is an end view of the generator and cooler with the generator - door open, exhibiting a drawer 35 within the generator and a wire basket which hangs in the drawer. Part of the end of the drawer is broken away. Fig. 3 is a detailed view of a spray-pipe, showing a cross-section and a side elevation with part of the side 40 broken away. It also shows a section of a nipple connected with the spray-pipe. Fig. 4 is an enlarged detail of a water-cut-off diaphragm distended and in section. Fig. 5 shows the way several generators may be 45 coupled together and connected with one cooler. This construction is used in the larger plants.

Throughout the drawings similar numerals and letters of reference refer to similar parts. 50 Speaking generally, the acetylene-gas machine which I have invented consists of a gen-

erator A, containing a drawer B and a wire basket B² hung in said drawer for the purpose of holding carbid of calcium, a spray-pipe C, running within said generator above 55 the drawer and basket, a gas-cooling drum D, with a pipe E connecting the generator and the cooler, an automatic water-cut-off device on said pipe which operates to cut off the supply of water to the generator when the pressure of gas exceeds a predetermined limit, a gas-cut-off device connected with said cooler D, which is also worked automatically by the pressure of gas, and a water-tank F, and a pipe G, which carries water from said tank 60 to the spray-pipe C in the generator A.

The generator A consists of a long galvanized-iron cylinder or drum lying horizontally and having a stationary head A' at one end and a hinged head A² at the other end. The 70 stationary head is made either of cast or galvanized iron, as desired, and is bolted or riveted gas-tight to one end of said cylinder. There is an annular flange A³ around the other end of the cylinder, which flange has a short 75 arm A⁴ projecting horizontally outward from its lower part and another short arm A⁵ similarly projecting from its top part. To the outer end of the lower arm A⁴ is hinged one end of a steel bar A⁶ by means of a bolt A¹⁰, 80 which passes through said arm A⁴ and through said bar A⁶. The bar A⁶ is as long as the diameter of the generator plus the width of the upper and lower arms, so that when it is swung upward its upper end is as high as the 85 top of said upper arm A⁵. The hinged head or door A², which closes the open end of the generator, is a plano-convex head, cast circular, with its convex side inward. Said head A² has two lugs A⁷, which extend from its plane 90 side in such a manner that the bar A⁶ fits snugly between them, and these lugs are fastened to the middle point of said bar A⁶ by a bolt A¹¹, which passes through them and through it. A U-shaped catch A⁸, adapted 95 to receive the upper end of the bar A⁶, is hinged to the upper arm A⁵ by a bolt A¹², which passes through said arm and through the ends of said U-shaped catch. Said ends fit one on either side of said arm. When the bar A⁶ is 100 raised, the head A² is raised with it, so as to entirely close the end of the generator that

is not provided with a stationary head, the catch A⁸ is swung down over the upper end of the bar A⁶, and the screw A⁹, which passes through the outer or loop end of the catch A⁸ 5 and points inward, is tightened, thereby forcing bar A⁶, and consequently the head A², into position and completely closing the open end of the generator.

The generator contains a sheet-iron drawer 10 B and a wire basket B², which holds the carbide of calcium. The wire basket is hung in the drawer, as hereinafter described. The drawer B is a little more than a half-cylinder and is so constructed as to fit easily within the 15 generator A. It is made a little shorter than the inside of the generator, so as to permit the gas to pass between its back end and the permanent head A' of the generator and also to allow room between front end and the generator- 20 door A² for a handle B³, which is fastened to the front end of said drawer. This handle B³ is for the convenience of a person in removing said drawer when it is necessary to recharge it with carbide and in replacing it when 25 full.

The basket B², which holds the carbide, is made of black iron wires. It consists of several longitudinal wires and several wires which run around these long wires and hold 30 them in position. The number of each set of wires is determined by the size of the basket. The longitudinal wires at the bottom of the basket are about an inch apart, and those near the top are a little wider apart. This is to 35 allow the slaked carbide to fall through. A wire runs across the top of each end of said basket, and wires run down from this latter wire to the cross-wire, which is at each end of the basket, thus forming an end for said basket, as shown in Fig. 2. Several hooks B⁴ 40 are provided on each side of said basket and so situated that they hook over the edge of the drawer and support said basket, keeping its bottom two or three inches above the inner surface of the bottom of the drawer, as shown in 45 Figs. 1 and 2. This space between the bottom of the basket and the drawer is to receive the slaked carbide as it falls down between the wires.

50 A spray-pipe C (shown in detail in Fig. 3) is fastened within the generator to the permanent generator-head A' and projects forward toward the open end of said generator above the drawer B and the basket B². This 55 pipe C is made of galvanized iron and is triangular in its cross-section. It is formed by bending up the sides to the proper shape and soldering the edges together. There is a row of holes C⁷ about two inches apart in the bottom edge of said triangular spray-pipe, as 60 shown in Fig. 3, and when the generator is in operation the water flows through them and sprays upon the carbide in the basket beneath. A short round pipe C² is soldered to 65 the end of said spray-pipe C next to the permanent generator-head A', and the other end of the spray-pipe is also made round and cov-

ered by a cap C³, which is screwed to it. The little piece of round pipe C² fits tightly within a nipple C⁴, fastened within the generator-head A'. The hole in the nipple C⁴, in which the round pipe C² fits, is made flaring, so that said pipe will easily enter it, and by simply pushing it in said hole it becomes perfectly tight. The round pipe C² is practically the 75 inner end of the spray-pipe C.

If the permanent generator-head A' is made of cast-iron, the nipple C⁴ is fastened in it by screw-threads on the outside of said nipple, that engage similar screw-threads on the inside of a hole in said permanent generator-head A'. There is a flange C⁵ on said nipple, which when the nipple is screwed into said generator-head A' fits closely against the outside of said head, and thus makes the connection air-tight. If the generator-head A' is made of sheet-iron, as shown in Fig. 3, it is necessary to provide a flange or nut C⁶ on the inside of said generator-head A' for the nipple C⁴ to screw into, because the galvanized iron is too thin to securely engage said screw-threads on the outside of said nipple C⁴. 80

The reasons for having the spray-pipe simply slipped in the nipple C⁴ and for having the cap C³ screwed upon the outer end of the spray-pipe are that the pipe may be easily taken out and swabbed clean whenever the little perforations become clogged with the impurities in the water. The object of having the spray-pipe C made triangular is that 95 a person replacing it after having cleaned it, as before described, will have no difficulty in determining what part of it should be turned downward. If it were shaped otherwise, this might be difficult, because the generator is 100 long and dark inside. A water-cock G² (of any desired design) is screwed onto the outer end of said nipple C⁴, and the water-pipe G is 105 screwed into the other end of said water-cock. The water-cock G² shown in Fig. 1 is a globe-valve and that shown in Fig. 3 is a conical valve. 110

The water-pipe G leads from the water-tank F, which is located above the generator A, to the nipple C⁴ and conveys the water from said 115 tank into the spray-pipe C, from whence it is allowed to spray upon the carbide. A check-valve G³ is provided in said pipe G and is so arranged as to prevent the gas from forcing its way back through the spray-pipe C and the pipe G into the tank F. A cut-off valve G⁴ is also placed in the pipe G and is provided with a long lever-handle G⁵, the operation of 120 which is described hereinafter.

The water-tank F is made of any suitable material, and its size is determined by the size of the generator. It is adjusted to hold just enough water to consume the carbide in the basket B², and when the water has been all used out of it the person operating the machine is 130 thereby informed that the generator needs to be recharged with carbide. The tank F may be supplied with water from any suitable source, as from the pipe F². 125

A gas-pipe E is connected with the generator, passes through the lower part of the permanent generator-head A', and conducts the gas to the cooler D below. Near the generator-head A' this pipe is provided with a coupling E² to enable a person to more easily connect its different parts, and a little farther from said head A' it has a check-valve E³ so arranged as to prevent the gas from flowing back from the cooler to the generator. Still farther in the course of said pipe E is a cross-coupling E⁴, the cross being perpendicular, as shown in Fig. 1. The pipe E from the generator is connected with the left opening of said cross-coupling, and the continuation of said pipe E is connected with the bottom opening of the coupling and conveys the gas down into the cooler D. A pipe E⁵, which is connected with the right opening of the cross-coupling E⁴, extends a few inches to the right and is provided with a gage E⁶. On the right end of this pipe E⁵ is a blow-off valve E⁷. In the top opening of the cross connection E⁴ is connected a short pipe E⁸, and the upper end 25 of the pipe E⁸ is connected with the under side of a cast-iron bowl H.

The bowl H and its connected parts are shown in detail in Fig. 4. Their purpose is to operate the water-cut-off valve G⁴. The bowl is about three inches deep, and its edge 30 consists of a flange H², which projects outward. A rubber diaphragm H³ (shown distended in Fig. 4) is fitted over the top of the bowl H, so that the edge of the rubber is even with the edge of the bowl at all points, and the rubber is firmly clamped in its position by a metal ring H⁴, that is bolted to the flange H² of the bowl below. A metal guide H⁵ is bolted to the top of the ring H⁴ and 35 curves upward and above the bowl H, so that a hole in the upper end of said guide is directly above the center of the diaphragm H³. A rod H⁶ passes through this hole in the guide H⁵ and extends downward to the diaphragm H³ and upward to the lever G⁵. At its lower 40 end this rod screws into a washer H⁸, and the washer rests upon the rubber diaphragm. At its upper end a pin H⁹ passes through it and through a slot G⁶ in the outer end of said lever G⁵, which is attached to the water-cut-off valve G⁴, as already described. A weight H⁷ is fastened to the rod H⁶ between the guide H⁵ and the lever G⁵ for the purpose of keeping said rod and the diaphragm beneath it 45 normally down.

When the pressure of gas in the pipe E gets too high, it operates to distend the diaphragm, as shown in Fig. 4. This raises the rod H⁶, and the rod in turn raises the outer end of the lever G⁵ and shuts off the water-supply to the generator, thus stopping the generation of gas until the pressure is relieved. The weight H⁷ forces the rod H⁶ and the lever G⁵ down as soon as the gas has been sufficiently drawn off and the pressure reduced, and thus the water is again turned on.

After the gas leaves the generator it passes

through the pipe E into a purifier and cooler D, located below the generator. This cooler is a galvanized-iron drum, considerably longer than the generator, as is shown in Fig. 1. The end of the cooler beneath the open end of the generator has a closed head. The other end has a flange D², which projects outward, and on it is clamped a rubber diaphragm J by a ring D³ in a similar manner that the ring H⁴ clamps the diaphragm H³ upon the bowl H. An iron partition D⁴ is fastened within the cooler D a few inches from the end covered with the diaphragm J by bolts D⁵, which pass through a flange D⁶, that runs around the circumference of said partition and through the shell of said cooler. It is located between said diaphragm J and the point where the pipe E enters the cooler, thus allowing the gas from the generator to enter the main body of the cooler. A nipple D⁷ screws into a hole near the top of the partition D⁴, and through this nipple the gas passes from the main chamber of the cooler D into the compartment between said partition and the diaphragm J.

A gas-cut-off valve J² is attached to the end of the nipple D⁷ next to the diaphragm J and is operated by a lever J³, which projects downward to a point about opposite to the center of the diaphragm J. A rod J⁴ connects with the lower end of this lever J³, passes through the center of said diaphragm J, and through a hole in guide J⁵. Guide J⁵ is a piece of iron bolted at each end to diametrically opposite points on the ring D³ and bows outward, so as to guide to the outer end of the rod J⁴ and to allow the diaphragm J to distend outwardly. The rod J⁴ is secured to the center of the diaphragm J (through which it passes) by lock-nuts J⁶. A wire spring J⁷ is placed around said rod J⁴, so as to press upon the guide J⁵ and the outer lock-nut J⁶ and keep the diaphragm J normally not distended, the rod J⁴ pressed inward, and the gas-cut-off valve J² open.

The gas is supplied to the burners through the service-pipe D⁸, connected to the lower part of the cooler within the compartment embraced between the partition D⁴ and the diaphragm J.

The gas is cooled and purified in the cooler D by being conducted by the pipe E down into water which about half fills said cooler and by being allowed to percolate or bubble up through it. All steam in the gas is thus condensed, and the other impurities with which gas coming direct from the generator is burdened are deposited in the water, and we have a cool, pure, and dry gas. The water can be introduced into the cooler through an opening in its upper side, which is stopped by the plug D¹⁰. The floating impurities can be drawn off through the faucet D¹¹, which is located a little below the water-line in the closed end of the cooler D. The remainder of the water and the heavier impurities are drawn off through the drain-cock

D⁷, which drain-cock is situated in the bottom of the cooler D.

Both the cooler D and the generator A are supported by the same set of legs K, as best shown in Figs. 1 and 2. The legs are made of wrought-iron and bent so as to conform to the shape of the cooler and passing upward form a support for the generator. The two front legs (and likewise the two back legs) are steadied and clamped together by bolts K², which pass through said legs beneath the cooler, and also by bolts K³, which pass through them between the cooler D and the generator A. A cross-rod K⁴ connects and braces the front legs with the back legs by being fastened to their respective bolts K³.

Fig. 5 is a modification of my invention (showing a larger machine than in Fig. 1) having more than one generator connected with one cooler. In this construction I find it most convenient to have the cooler placed beneath and at right angles to the generators. There may be any number of generators, according to the size of the machine, connected with one cooler, and they may be arranged with relation to one another and the cooler in any convenient way.

My invention operates as follows: The carbid of calcium is placed in the basket B², and the generator-door A² is closed and locked by the bar A⁶ and the catch A⁸. The water is then turned on from the tank F and runs through the pipe G and the spray-pipe C down upon the carbid, whereupon acetylene gas is immediately generated. The gas then passes back of the rear end of the drawer B and down through the pipe E into the drier and cooler D. When the gas is generated, it is hot and full of impurities, such as steam and particles of carbid. These are all allowed to settle in the purifier and cooler D, and the gas passes out through the nipple D⁵, and thence down into the service-pipe D⁶ and to the burners. The water being turned on at full force, the gas is usually generated faster than it is consumed. Accordingly the pressure increases in the generator and cooler and connected pipes until the diaphragm J becomes distended, and thus shuts off the supply of gas through the gas-cut-off valve J². This confines the gas within the cooler, generator, and pipe E, which connects them. Then the pressure of gas on the under side of the diaphragm H³ distends it, and so closes the valve G and cuts off the supply of water to the generator and stops the generation of gas. As soon as the pressure of gas in the service-pipe and in the small compartment of the cooler becomes reduced the diaphragm J resumes its normal position, opens the valve J², and relieves the pressure of gas in the cooler, and consequently upon the diaphragm H³. This latter diaphragm then resumes its normal position, the valve G⁴ is opened, and the generation of gas is commenced. In practice the diaphragms keep vibrating, thus slackening or increasing

the generation, and seldom is it necessary to entirely shut off the water-supply.

One of the chief merits of my invention is that I maintain the gas at a uniform pressure, and it is not necessary to use a gasometer; nor is it necessary for a person to be constantly in attendance upon it, because the diaphragms and parts connected with them work entirely automatically.

Although the drawings show a machine capable of being used without a gasometer, it can be used with one. In this event the diaphragms and parts particularly connected with them are done away with, and the water-supply cock may be operated by the rise and fall of the inner tank of the gasometer, and although the drawings show the cooler D partially filled with water it will operate to produce a reasonably dry, cool, and pure gas if the water is omitted, because the cooler is spacious and of itself affords a large cooling surface for the gas.

Having now described my invention, what I claim, and desire to secure by Letters Patent of the United States, is—

1. In an apparatus of the kind described, the combination of a generator, a water-supply, a cut-off valve therefor, a tank communicating with the generator and comprising a main chamber and a compartment communicating therewith, a diaphragm actuated by gas-pressure in said tank, connection from said diaphragm to said cut-off valve, a valve controlling said communication between the tank-chamber and compartment, a diaphragm actuated by gas-pressure in said compartment, connections from said diaphragm to said last-mentioned valve, and a gas-pipe from said compartment, substantially as described.

2. In an acetylene-gas apparatus, the combination of a generator containing the gas-producing material, a pipe leading into the same for supplying liquid, a cut-off valve in said pipe, a cooling-tank, a pipe leading from the generator to the cooling-tank, a cross connection for said pipe intermediate the generator and the cooling-tank, an inflatable diaphragm on one member of said cross connection, connecting means between said diaphragm and cut-off valve, and a blow-off valve also connected with another member of said cross connection, substantially as set forth.

3. In an apparatus of the kind described, a generator having a nipple in one of its ends and a perforated spray-pipe triangular in cross-section removably held in said nipple, substantially as described.

4. In an apparatus of the kind described, a generator having a triangular spray-pipe provided with holes in its bottom edge, and means to removably secure said pipe in position within said generator, substantially as described.

5. In an apparatus of the kind described, a generator having a triangular perforated

spray-pipe with a round end and a nipple with a flaring hole adapted to receive the round end of said pipe, substantially as described.

5 6. The herein-described spray-pipe having the triangular body with holes in its bottom edge, the round extension at one end, a nipple having a smooth bore into which said round extension is slipped, and the removable cap at its other end, substantially as described.

7. An apparatus of the kind described comprising a generator containing gas-producing material, a water-pipe discharging into the 15 same, a cut-off valve in said water-pipe, a cooler receiving the gas from said generator, means actuated by the gas operating to open and close said cut-off valve according to the pressure in said cooler, an inflatable diaphragm secured to one end of the cooler and separated from the body of the same by a partition, a pipe passing through said partition and discharging the gas in the space comprised between it and said diaphragm, a 20 service-pipe drawing gas from said space, a cut-off valve in the partition-pipe, a lever at-

tached to the latter-named valve, and a suitably-guided spring-pressed rod attached to the diaphragm and pivotally connected to said lever, substantially as described. 30

8. In an apparatus of the character described, the combination of a generator, a water-supply, a cut-off valve therefor, a tank communicating with said generator comprising a main chamber and a compartment communicating therewith, a device actuated by the gas-pressure in said tank, connection from said device to said cut-off valve, a valve controlling said communication between said tank-chamber and said compartment, a diaphragm actuated by gas-pressure in said compartment, connection from said diaphragm to said last-mentioned valve, and a gas-pipe from said compartment, substantially as described. 35 40 45

Signed by me at San Francisco, California, this 9th day of January, 1899.
